UNITED STATES PATENT OFFICE.

IRA KLECKNER, OF CAMDEN, INDIANA.

ROTARY ENGINE.

No. 860,549.

Specification of Letters Patent.

Patented July 16, 1907.

Application filed May 5, 1906. Serial No. 315,425.

To all whom it may concern:

Be it known that I, IRA KLECKNER, a citizen of the United States, residing at Camden, in the county of Carroll and State of Indiana, have invented certain new and useful Improvements in Rotary Engines, of which the following is a specification.

This invention relates to improvements in steam engines of the rotary type in which a cylindrical piston is mounted within and concentrically to a steam cylinder, and in which the steam enters the center of the piston on one side and passes out on the opposite side, and in which there are fixed and sliding abutments against which the steam impacts and rotates the piston.

15 The especial objects of my improvements, are to produce an engine of the type named which will be of simple and economical construction, in which the frictional surfaces will be reduced to the minimum and in which the expansive force of the motive power 20 fluid will be conserved in the maximum degree.

The minor objects obtained through my improvements are the accurate movements of the sliding abutments and simple and effective provision for reversing the direction of the engine.

25 In the accompanying drawings which form a part of this application for patent, I have shown my improved rotary engine in the following views:—

Figure 1 is a vertical section through the center of the engine; Fig. 2 is a cross-section just above the 30 horizontal axis of the engine; Fig. 3 is a side elevation of the engine, and Fig. 4 is an edge view of the piston.

Referring to the drawings in detail A, A¹, represent the two cylinder plates which form the engine cylinder and the same are secured together by bolts 35 through their co-registering flanges a², leaving a cylindrical steam chamber a³ having a rounded periphery as shown in Fig. 2. In this chamber is mounted concentrically with the cylinder, a hollow cylindrical piston B on the periphery of which are fixed radial 40 abutments b¹, b¹, which are spaced apart and in the spaces therebetween, are loosely mounted expansive packing-rings b² which provide steam tight joints between the flanges b¹ and the inner walls of the cylinder. The piston is cast with steam passages b³, b⁴, 45 which enter through the hubs b⁸ of the piston, extend radially through the piston in opposite directions and pass out at opposite points in its periphery. These passages serve respectively and alternately as induction and eduction conduits and ports depending upon 50 the direction in which it is desired to drive the piston. The cylinder plates are formed with extensions a⁶ at opposite peripheral points to which are secured stuffing boxes a⁵ of well known form. Through said extensions are slide-ways a⁴ the inner ends of which communicate with the steam chamber a³. Arranged in 55 the slide-ways a⁴ are slidable abutments c² c² to the

outer edge of which are secured rods c¹, c¹, which pass through suitable openings in the stuffing boxes a⁵ and have nuts c⁴ mounted on their outer end-portions.

Secured to the rods between the nuts c⁴, are U-shaped 60 yokes C the ends of which are connected with coil-springs c⁵ which in turn have their opposite ends secured to lugs on the opposite faces of the cylinder as shown in Fig. 2. The normal tension of said springs is exerted to draw said yokes inwardly or toward the center of the cylinder and inasmuch as the sliding abutments are connected with said yokes through the rods c¹ the retractile power of the springs will be transmitted to said abutments.

Near the free ends of the yokes C are fixed square 70 pins which are adapted to slide between the forked ends d² of the bars D arranged on opposite sides of the cylinder. Each of the bars D is formed with a boss d¹ near one end on which is pivoted the free end of the arm e² of the cam-ring e¹ which is fitted on the cam E. 75 This cam is eccentrically mounted on the hub portion b⁸ of the piston and rotates with the latter. A pulley F is mounted on one of the hubs of the piston, and steam is conducted to or from the passages b³, b⁴, by pipes g¹, g², between the ends of which and the said passages 80 steam tight joints are effected by the stuffing boxes b⁶ in the usual manner.

It will be understood from the foregoing description that the construction and arrangement of cam, cam-ring and bar D are the same on both sides of the cylinder. It will also be understood that the sliding abutments are so mounted, connected and operated as to alternately close or block the steam chamber between the periphery of the piston and the walls of the cylinder. 90

From the construction above described it will be apparent that steam entering through the pipe g¹ will pass through the passage b⁴ and out at the periphery of the piston, whereupon the slideable abutment c² being across the chamber a³ as shown in Fig. 1, the steam will 95 impinge against the abutments b¹ of the piston and push same circumferentially of the cylinder and thereby rotate the piston; when the abutments b¹ pass the slide-way of the sliding abutment c² on the opposite side of the cylinder, the first named sliding abutment 100 will begin to retract and thus will permit the steam to enter the passage way b³ and pass therethrough and out the pipe g², in the meantime, the supply of steam being continued, it will enter the space between the piston abutment b¹ and the second sliding abutment c² 105 which will have been closed through the co-action of the cam E and its connecting rod D the yoke C and the springs c⁵ as described, thus forming a second expansion chamber for the steam which will give further impetus to the piston and continue its rotation. 110

I have not shown any means for reversing the introduction of the steam from the pipe g¹ to the pipe g²,

because any reversing slide valve arranged to control both of said pipes, will answer such purpose, and same forms no essential part of my invention which relates particularly to the construction of the engine proper.

5 Having thus fully described my invention what I claim as new and desire to obtain by Letters Patent, is:—

10 1. In a rotary engine, a cylindrical steam cylinder, a cylindrical piston having axial and radial passages therethrough substantially as shown, and provided with fixed abutments on the periphery of the piston, slideable abutments mounted on opposite sides of the cylinder, U-shaped yokes connected with said abutments, and means for operating said yokes including spiral springs; substantially as described.

15 2. In a rotary engine, a cylinder, a cylindrical piston mounted within and concentrically to said cylinder and provided with axial and radial inlet and outlet passages, slideways in opposite sides of said cylinder, abutments

slidably mounted in said slide-ways, U-shaped yokes connected with said abutments, spiral springs connected with said yokes and adapted to retract the same, and eccentric means for moving said yokes against the tension of said springs. 20

3. In a rotary engine, a cylinder, a cylindrical piston mounted within said cylinder and provided with communicating axial and radial inlet and outlet passages respectively, slide-ways in said cylinder, abutments slidably mounted in said slide-ways, yokes connected with said abutments, springs adapted to retract said yokes, and 25 means for moving said yokes against the tension of said springs consisting of cams cam-rings and slotted bars, substantially as described. 30

In testimony whereof I affix my signature in presence of two witnesses.

IRA KLECKNER.
